CLAIM

The ornamental design for a portable radio receiver, as shown and described.

DESCRIPTION

FIG. 1 is a front, top and right side perspective view of a portable radio receiver showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a left side elevational view thereof.

In FIGS. 4 to 7 the handle is shown in its horizontal position for convenience of illustration.

FIG. 1

FIG. 2

FIG. 3

FIG. 4

FIG. 5

FIG. 6

FIG. 7
